UNITED STATES PATENT OFFICE.

HERBERT S. SMITH, OF NEW YORK, N. Y., ASSIGNOR OF ONE-HALF TO
CHARLES DEXTER ALLEN, OF NEW YORK, N. Y.

ENVELOP.

SPECIFICATION forming part of Letters Patent No. 767,449, dated August 16, 1904.

Application filed November 6, 1903. Serial No. 180,034. (No model.)

To all whom it may concern:

Be it known that I, HERBERT S. SMITH, a citizen of the United States, residing in New York, in the county of New York and State 5 of New York, have invented certain new and useful Improvements in Envelops, of which the following is a specification.

This invention pertains to envelops or bags, and more particularly to the manner of closing them through the instrumentality of 10 specially-devised forms of flaps or flies.

Among the apparent objects those calculated to effect absolute closure are important, also to provide an inexpensive, durable, and 15 efficient article of manufacture.

Referring to the drawings forming a part of this specification, Figure 1 illustrates perspectively the envelop or bag, one of the flaps of which is lengthened, and the view is also 20 broken away to show the manner of closure. Figs. 2 and 3, respectively, indicate the manner of closing with the lengthened flaps or flies. Fig. 4 illustrates an envelop with its flaps extended still farther than those shown 25 in the previous figures, and the closure is partly broken away to show the arrangement. Fig. 5 illustrates an envelop with the flaps or flies suitably creased, as seen in Fig. 6, and the view is broken away to show the relation 30 of the flaps or flies when closed. Fig. 7 illustrates the flaps or flies provided with a tongue formed from the material of the bag and slit, whereby the closure may be interlocked, as seen in Fig. 8.

35 Similar characters of reference indicate like parts in all the views.

The envelop or bag will be generally indicated by 1 and which may open at any desirable point. In the present case such opening 40 may be at the end, as 2.

The open end of the envelop may be provided with flaps 3 and 4, respectively.

As to the construction of the envelop or bag 45 1, this may be of any suitable type, it being shown merely in illustration that said envelop may be pasted along its edges 5 and 6 or in any other suitable manner.

The flaps, which in the present instance 50 may be generally designated by 3 and 4, may be of any suitable construction. As shown,

they may consist of two extensions 7 and 8 on the walls of the envelop or bag. Again, the flaps 7 and 8, respectively, may be further lengthened, and one may be of greater length than 12, the latter, if so desired, being provided with one crease, while its mate may be provided with two such or similar creases, when the extreme fly 13 of the flap 12 may be overturned into place against the fly 14 and then the operation repeated, overturning 60 the fly 15 against the fly 16, whereby to make a reinforced closure, as seen at 17 of Fig. 4.

The arrangement shown in Figs. 5 and 6 is similar to that shown in Figs. 1, 2, and 3. In this case, however, the flies 25, 26, 27, and 65 28, respectively, may each be the same length, and being suitably creased, as shown, the closure may be effected as illustrated in Figs. 5 and 6. In the flies 26 or in any of the others aforementioned there may be provided a slit 70 29, and one of the flies, as 28, may be suitably cut to form a tongue 30, which may be introduced into the former, as seen in Fig. 8, or both flies may be cut identically alike, so as to fold or close interchangeably at will. 75

Thus it will be seen that there is provided an envelop or bag having two or more flaps adapted to close into each other and form a substantial closure. Also by such structure and arrangement the use of gum or adhesives 80 for closing purposes is rendered unnecessary, although the same may be employed, if desired. Furthermore, the closure construction may, if desired, be placed on any or as many ends of the envelop as necessary or 85 desired. It will also be observed that such a closure as is provided will have an accordion effect, giving it displacement to accommodate the thickness of contents without straining or breaking the closure. 90

It will be seen that I provide an envelop or bag having at its opening a pair or plurality of interlocking or interfolding flaps whereby to provide an absolute closure.

It might be said that each flap of the closure 95 is provided with pockets into which the other flap is disposed when the closure is completed.

Within the purview of this invention it is to be understood that variations may be resorted to.

It will be observed that the flaps or folds hereinbefore mentioned are interchangeable, whereby they can be interfolded by inserting either one into the opening first.

Having thus described my invention, I claim—

1. An envelop or bag from the material of the body portion of which extend two flaps for forming the closure, each flap comprising two flies of substantially equal length whereby one flap may be inserted into the other and vice versa when inserted into the bag to form said closure, each of said flies being foldable upon itself and interfoldable with the other fly.
2. An envelop or bag, from the material of the body portion of which extend two flaps for forming the closure, each flap comprising two flies of equal length so constructed or formed as to be interchangeable for insertion into the bag to form said closure, a slit in one of the flies, and a tongue formed on another whereby the interfolding flies may be locked.

Signed at Nos. 9 to 15 Murray street, New York, N. Y., this 5th day of November, 1903. 25

HERBERT S. SMITH.
